RAILWAY BRAKE BEAM

Louis Kadar, Chicago, Ill., assignor to Chicago Railway Equipment Company, Chicago, Ill., a corporation of Illinois

Application October 14, 1936, Serial No. 105,497

10 Claims. (Cl. 188—222)

The invention relates to railway truss type brake beams in which a tension member is anchored at its ends to the ends of a compression member, either directly or through an intermediate brake head or other thrust block structure.

It has been customary to form the tension member of a round rod and to thread its end portions and provide nuts thereon seated against bearings on the brake heads or ends of the compression member. Beams of this familiar type are subject to breakage of the tension rod adjacent the anchorage to the compression member, and the main object of the present invention is to eliminate such breakage by avoiding reduction of the cross section of the tension member at the point of anchorage to the compression member without sacrificing the feature which has made the above described type of beam universally desirable, namely, the capacity for maintaining the truss structure in a tight condition by increasing the tension on the rod by tightening the nuts.

An additional object of the invention is to secure the desired result without the use of special brake head or other unusual parts which would conflict with parts covered by American Railway Association standards.

In the accompanying drawing which illustrates various embodiments of the invention—

Figure 1 is a top view of a typical truss brake beam embodying one form of the invention.

Figure 2 is a front elevation of the same.

Figure 3 is an enlarged detail section taken approximately on the line 3—3 of Figure 2.

Figures 4 to 8 are detail sections corresponding to Figure 3 but illustrating respectively different modifications.

In Figures 1, 2 and 3, the compression member 1 is of channel or U cross section and is cambered from end to end in the usual manner. A strut 2 is seated intermediate the ends of the compression member and the brake heads 3 are seated on the ends of compression member 1. Tension rod 4 passes over strut 2 and through brake heads 3 projecting laterally of the latter in the usual manner. Rod 4 maintains its smooth periphery throughout its length except that the extreme end is upset to provide a head 5 having a bearing 6 facing towards the adjacent brake head 3. A sleeve 7 surrounds the end portion of tension member 4 with its outer end seated against bearing 6. Sleeve 7 is threaded exteriorly and a nut 8 may be screwed thereon until seated against the bearing 9 provided on the outer face of the brake head. Preferably

the inside diameter of the threads on sleeve 7 is greater than the outside diameter of head 5 whereby the nut may be applied and removed over head 5 to permit application and removal of the brake head for initial assembly, repairs or replacement. Preferably bearing 6 on head 5 has a spherical contour and the corresponding end of sleeve 7 is similarly shaped whereby variations in the angle between the compression member and the tension member are accommodated and there is an even distribution of thrust forces between head 5 and sleeve 7 and between nut 8 and brake head bearing 9.

Obviously the tension rod 4 retains its full sectional area throughout its length which results in marked increase in service life over the usual threaded tension rod irrespective of any slight increase in diameter which may be provided to insure a tight fit with the sleeve 7 which fit is not essential.

In Figure 4, the exteriorly threaded sleeve 10 is seated against a pin 11 extending transversely through the outer portion of rod 12. Nut 13 engages sleeve 10 and the bearing on head 14 as in the previously described structure. Rod 12 is shown with its end portion 15 upset to provide increased sectional area at this point and to compensate for the metal removed to accommodate pin 11. This arrangement, while preferable, is not necessary to provide the rod with increased resistance to the forces tending to break the usual tension rod adjacent to its anchorage to the compression member of the beam. Preferably sleeve 10 loosely surrounds the tension rod and can pivot about pin 11 to accommodate forces tending to vary the angle between tension rod 12 and compression member 16.

In Figure 5, a relatively wide, flat key 22 is substituted for the pin 11 shown in Figure 4, otherwise the structures are identical.

In Figure 6, the enlargement at the end of the tension member 17 takes the form of the pin 18 corresponding to that shown in Figure 4 but the structure includes a washer 19 intermediate pin 18 and sleeve 20, the washer and sleeve having opposing convex-concavo bearing faces further facilitating the resulting variations in the angular relation between the tension member 17 and the compression member 21.

In Figure 7, the outer end of threaded sleeve 23 is provided with a square or hexagonal head 24 adapted to be engaged by a wrench to provide a tightening operation in addition to that afforded by nut 25. In this form of the invention the extreme end 26 of the tension rod may be upset,

as indicated at 27, to form the bearing for the sleeve.

5 In Figure 8, the enlargement of the tension rod 28 takes the form of a stud 29 threaded into an opening provided therefor in the end of the tension rod. Sleeve 30 is seated against the inner face of the head of stud 29 and mounts nut 31 as do the sleeves in the previously described forms of the invention.

10 In each form of the invention the sectional area of the rod is maintained adjacent to the mounting of the brake head on the compression member, there being no reduction in the cross sectional area abreast of the bearings even to the extent resulting from the cutting of threads, although the rod anchorage includes a desirable threaded nut arrangement whereby the beam may be cambered, slack may be taken up, pin holes may be adjusted, and internal tension within the brake head itself may be assured to the same extent as in the usual form of truss type brake beam heretofore in use.

15 In some truss type brake beams the compression and tension members are not anchored to the brake head but to a separately formed thrust block upon which the brake head is mounted in such manner as to be free of the truss tension. I consider the thrust blocks of such means as the equivalent of the brake head shown in the accompanying drawing so far as the present invention is concerned. Other variations in details may be made by those skilled in the art without departing from the spirit of the invention and exclusive use of such modifications as come within the scope of the claims is contemplated.

20 What is claimed is:

25 1. In a railway truss type brake beam, a compression member, a tension element, a brake head seated on said compression member, a sleeve member surrounding the end portion of said tension element and anchored thereto, and means operatively engaging said sleeve member and said brake head to adjust the truss tension.

30 2. In a railway truss type brake beam, a compression member, a tension element, a sleeve member surrounding the end portion of said tension element and anchored thereto, and means for tensioning said element seated against one of said members and movably mounted on the other of said members.

35 3. In a railway truss type brake beam, a compression member, a tension element, a sleeve member surrounding the end portion of said tension element and anchored thereto, a nut threaded on said sleeve member, and means transmitting the thrust of said nut to said compression member.

40 4. In a railway truss type brake beam, a compression member, a brake head seated thereon, a tension element passing through said head and having an enlargement near its outer end form-

45 ing a seat facing towards said brake head, and tensioning means comprising a pair of cooperating parts movable along each other longitudinally of said tension element and engaging said head and seat respectively and arranged to thrust in opposite directions thereon. 5

5. In a railway truss type brake beam, a compression member, a brake head seated thereon, a tension member extending through said brake head and being provided at its outer ends with a seat facing towards said brake head, a tensioning device engaging said brake head and seat and having a rocking bearing on said seat to accommodate play between said tension member and said compression member. 10

6. In a railway truss type brake beam, a compression member, a tension member having a smooth periphery for a substantial distance inwardly from its end, a sleeve enclosing the smooth peripheral portion of said tension member and fixedly secured thereto, and means exerting thrust in opposite directions against said sleeve and compression member for tightening the truss structure. 15

7. In a railway truss type brake beam, a compression member, a brake head seated thereon, a tension member extending through said brake head and having an unthreaded end portion, and a threaded device secured to said end portion of said tension member and operative to tighten up the tension of the beam. 20

8. In a railway truss type brake beam, a compression member, a brake head seated thereon, a tension member extending through said brake head, an element extending transversely through the end portion of said tension member and projecting laterally therefrom, and a tensioning device seated against said brake head and element. 25

9. In a railway truss type brake beam, a compression member, a tension element, a sleeve member loosely surrounding the end portion of said tension element, the outer end of said tension element being provided with a lateral projection, said sleeve member being pivotally seated on said projection, a nut threaded on the exterior of said sleeve member, and means transmitting the thrust of said nut to said compression member. 40

10. In a railway truss type brake beam, a compression member, a tension member, a strut between said members, said compression member having a bearing facing away from the end of the beam, the sectional area of said tension member between said strut and bearing being maintained past said bearing, a sleeve enclosing said tension member adjacent said bearing, and means engaging said sleeve and movable relative to said sleeve and tension member and positioned outwardly from said bearing and operative to thrust said sleeve towards said bearing. 45 50 55
